UNITED STATES PATENT OFFICE.

WELLINGTON PARKER KIDDER, OF BOSTON, MASSACHUSETTS, ASSIGNOR
TO FRANK H. GOODYEAR AND GEORGE E. MATTHEWS, TRUSTEES, OF
BUFFALO, NEW YORK.

PORTABLE ENGINE FOR USE IN REMOVING BARK FROM STANDING TREES, &c.

SPECIFICATION forming part of Letters Patent No. 739,785, dated September 22, 1903.

Original application filed October 4, 1902, Serial No. 125,998. Divided and this application filed October 4, 1902. Serial No. 125,999. (No model.)

To all whom it may concern:

Be it known that I, WELLINGTON PARKER KIDDER, a citizen of the United States, residing at Boston, in the county of Suffolk and State of Massachusetts, have invented certain new and useful Improvements in Portable Engines for Use in Removing Bark from Standing Trees and other Purposes, of which the following is a specification, reference being had therein to the accompanying drawing, showing a top plan view of my new portable engine.

The object of my invention is to produce a light-weight portable engine which may be readily temporarily anchored *in situ* and which is adapted to raise and lower implements used in removing bark from standing trees and also provide such implements with compressed air for their actuation.

My new engine is illustrated, but not claimed, in my application, Serial No. 125,998 of even date, for apparatus for removing bark from standing trees.

In the drawing, 1 is the engine-base, of any suitable construction, preferably provided with lateral wings 2, there being one wing at each corner of the base 1. These wings are preferably bored at 3, so that stakes or pins may be driven therethrough into the ground to hold the base and its supported parts in place temporarily. The base is also provided with an opening 4 in an anchoring device in the form of a bight 7 on that side from which the winding-drum 5 projects to receive the wound-on chain 6. Through the bight 7 a stake 5 may be driven to help anchor the engine temporarily in place, and especially to resist the pull on the chain 6 taken up on the winding-drum. The foregoing statement is made for the sake of clearness, but is only incidentally relevant to the main novelty of my present invention.

Base 1 supports a motor 9 of any suitable kind or construction, and therefore I do not herein specifically describe the motor further than to state that its driving-shaft 10 is provided with a small gear 11. Next to the mo-

tor I secure on the base an air-compressor 12 and air-receiver 13, which is connected with the air-compressor by the usual conduit 14. 50

The air-compressor and air-receiver may be of any desired construction, and hence I do not specifically describe the present compressor and air-receiver, which, like the motor, are of varying constructions and kinds 55 and known in detail to all persons skilled in the arts to which they relate.

In carrying out my invention I lengthen the usual transverse shaft 15 of the air-compressor (and which has heretofore been used, so far as I am advised, solely for the purpose of actuating the piston-rod and piston) and make it long enough to project from the side of the air-compressor, and on the projecting end of said transverse shaft 15 I mount the winding-drum 5, fixing it thereon conveniently by means of the pin 18. The other end of the shaft 15 is provided with the usual driving-gear 19, which intermeshes with the gear 11 of the motor, but which in the present instance is made much larger than the gear 11, so as to reduce the speed with which the winding-drum 5 rotates sufficiently to adapt the engine as a whole to a proper speed of travel of a rossing apparatus 75 attached to it up and down the standing tree-trunk. The rope 6 is the fall of the tackle, whereby the rossing implements are raised and lowered along the tree-trunk. That portion of rope 6 which is, as here shown, forward of the air-receiver leads to the rossing apparatus, while the stub or rear end of the rope 6 is conveniently held by the engine attendant and tightened or slackened on the drum, as the operator of the rossing instruments directs. Rope 6 is readily removable from winding-drum 5. The air-receiver is provided with a nozzle having a shut-off valve 21 and adapted for attachment of the pneumatic tube leading from the air-receiver to 85 the pneumatic rossing implements.

When the pneumatic tube 22 and rope 6 are detached from the engine and the anchoring-stakes are pulled up, the engine is in

readiness for transportation and may be carried up mountain sides and through jungles to any desired point.

My new engine provides suitable means for 5 supplying lifting power and compressed air to whatever apparatus may be used in stripping the bark.

I have described my new engine with particular reference to that particular industry 10 in which I contemplate its main use; but I desire to be understood as claiming my invention for any and every purpose for which it is or may be found useful.

What I claim is—

The combination of a base-plate; a motor having a shaft; an air-compressor having a shaft; a small gear on the motor-shaft; a relatively larger gear on the air-compressor shaft and meshing with the smaller gear on the motor-shaft; and a winding-drum on the 20 shaft of the air-compressor.

In testimony whereof I affix my signature in presence of two witnesses.

WELLINGTON PARKER KIDDER.
